INDICATING CURRENT LIMITER WITH PARTICLE-FILLED BODY

Irving F. Matthysse, Norwalk, Conn., and Leonard Greer, Bogota, N. J., assignors to Burndy Engineering Co., Inc., a corporation of New York

Application April 15, 1953, Serial No. 349,070

4 Claims. (Cl. 200—121)

Our invention relates to current limiters and more particularly to a current interrupting device having visible indication of its condition.

Objects of our invention are to provide a lightweight airtight, accurate limiter for aircraft adapted to withstand increased generator capacities and voltages used in present day aircraft without danger of explosion occurring during the interruption, and which will give a positive and easily visible indication of its condition.

These and other objects we accomplish and obtain our new results as will be apparent from the device described in the following specification, particularly pointed out in the claims, and illustrated in the accompanying drawings, in which—

Fig. 1 is a plain view, partly in section, of an embodiment of our indicating current limiter;

Fig. 2 is a side elevation thereof;

Fig. 3 is a cross-sectional view taken in the plane 3—3 of Fig. 2;

Fig. 4 is an end view of our device.

Fig. 5 is a perspective view of the indicator.

Our device comprises a glass tubular enclosure 10 mounted to a pair of knobs 12 provided with finger shields 14, a pair of contact blades 16 and 18, a fusible element 20, and arc suppressing means 22.

The glass enclosure which may be made of Pyrex, is capable of withstanding differential temperature conditions and shock without breakage. The knobs are made of insulating material, such as a phenolic resin having shield portions overhanging the blades, so as to prevent contact therewith during installation or removal. The knobs are recessed as at 24 and 26 forming sockets to receive the ends of the glass. The fusible element 20 is usually made of silver wire brazed to the copper blades which support the element substantially centrally of the glass tube.

The tube is filled with clean sand particles which form the arc suppressing means 22. Such sand particles normally cover the fusible element and prevent the condition of the limiter from being ascertained. In order to permit such inspection, we provide an indicator link 28, made of Nichrome ribbon and brazed to the end contact blades 16 and 18, in parallel with the silver fusible element 20. The link 28 extends from the contact blades towards the inner surface of the glass envelope to which it is attached by a suitable adhesive. A silicon grease has been used successfully between the link and the glass to prevent entrance of the sand particles which would obscure the vision of the observer. The silicon grease or cement will also act as a heat barrier between the link and the glass envelope. A cross-shaped link with centrally extending portions 30 aids in positioning and sup-

porting the link on the inner surface of the glass envelope.

The silver fusible element being more conductive will carry most of the current. When interrupted centrally within the sand filling, the current will be bypassed to the Nichrome wire which normally carries a small fraction of the main load. When the Nichrome link on the inner surface is interrupted, it will be readily apparent to the observer.

10 All the joints are fully sealed with cement 32 to prevent leakage, which permits the limiters to be used by aircraft at various heights with uniform limiter ratings.

15 For a readily discernible inspection of the condition of the fuse, a bright color changing paint is used which will discolor noticeably when the fuse is blown. An example of such indicating paint is identifiable on the open market as Pyromark, a trade product of the Tempil Corporation of New Jersey.

We have thus described our invention, but we desire 20 it understood that it is not confined to the particular forms or uses shown and described, the same being merely illustrative, and that the invention may be carried out in other ways without departing from the spirit of our invention, and, therefore, we claim broadly the 25 right to employ all equivalent instrumentalities coming within the scope of the appended claims, and by means of which objects of our invention are attained and new results accomplished, as it is obvious that the particular embodiments herein shown and described are only some 30 of the many that can be employed to attain these objects and accomplish these results.

We claim:

1. A current limiter having a fusible element, a transparent envelope body therefor, and contacts extending 35 therefrom, said envelope containing an inert substance enclosing the fusible element for absorbing the molten fuse particles when the circuit is interrupted, said fusible element having a parallel circuit of high resistance metal contained within the envelope body and extending toward the inner surface of the envelope body and barrier means for preventing the inert substance from entering between the high resistance metal and the envelope causing said high resistance metal to be visible there-through at all times for indicating the condition of the 40 limiter, said high resistance metal being provided with a heat discoloring surface.

2. The current limiter of claim 1, wherein the colored 45 high resistance metal is secured to the inner surface of the envelope.

3. The current limiter of claim 1, wherein a silicone 50 grease is positioned between the high resistance metal and the envelope body to block the inert substance from passing therebetween.

4. The current limiter of claim 1, wherein the colored 55 high resistance metal is cross-shaped, one of the cross-shaped sections peripherally extending around the inner surface of the envelope to keep the high resistance metal close to the surface thereof.
